UNITED STATES PATENT OFFICE.

KARL RÖGER, OF BERLIN, GERMANY, ASSIGNOR TO LINOTYPE AND MACHINERY LIMITED, OF LONDON, ENGLAND.

DEVICE FOR WIPE THE PRINTING-SURFACES OF INTAGLIO-PRINTING PRESSES.

1,102,548.

Specification of Letters Patent.

Patented July 7, 1914.

Application filed March 28, 1914. Serial No. 827,798.

To all whom it may concern:

Be it known that I, KARL RÖGER, a subject of the German Emperor, residing at 33 Telzwerstrasse, Berlin, in the Empire of Germany, have invented new and useful Improvements in Devices for Wiping the Printing-Surfaces of Intaglio-Printing Presses, of which the following is a specification.

This invention relates to devices for wiping the printing surfaces of intaglio printing presses and it has for its object to provide a novel construction of wiper which is capable of being adjusted so that it can exert greater or less pressure upon the surface to be wiped.

The invention will be best understood by reference to the accompanying drawings in which:—

Figure 1 is a diagrammatic cross section through part of a printing press provided with one form of the improved wiper; Fig. 2 is a horizontal section taken substantially on the line 2—2 of Fig. 1, and Figs. 3 to 7 both, inclusive, are diagrammatic cross sections of respectively different forms of the improved wiper.

Throughout the several figures of the drawing, like reference numerals indicate like parts.

In the arrangement shown in Fig. 1, 1 is the form or plate cylinder, 2 the intaglio printing plate or surface thereon, 3 a trough containing the ink 4 in which the cylinder 1 rotates so that the intaglio surface picks up the desired quantity of ink.

5 is an impression cylinder formed of, or clothed with, a suitable resilient material, and between which and the form cylinder 1, the web 7 is passed to receive the impressions from the printing surface 2.

8 are rollers which serve to guide the web 7 on either side of the impression cylinder 5, and 9 is a pressure cylinder in peripheral contact with the impression cylinder 5.

10 is the improved wiper which, in the construction now under review, consists of a frame 11 of approximately semi-cylindrical form, integral with disk-shaped ends 12 by which it is mounted, with a capacity for angular adjustment, on a non-rotatable shaft 13. Each of the ends 12 is provided with an arched slot 14 through which extends a stud 15 rigidly secured at its inner end in a disk or collar 16 which is fast on the shaft 13, in close juxtaposition to the respective

end 12. On the outer end of each stud 15 is a winged nut 17 by which the frame 11, after angular adjustment about the shaft 13, can be secured in any such position of adjustment. On the outer curved side of the frame 11, there is secured a shell or wiper proper 18, which is formed of metal or other suitable material having the required degree of resilience. As shown best in Fig. 1, the shell 18 is of substantially cylindrical form, that is to say, it is cylindrical excepting for a gap 19 which extends longitudinally from end to end thereof. By this construction of wiper, different parts of the shell 18, are capable of exerting relatively different degrees of pressure on the printing surface 2, according to whether those parts are directly supported by the frame 11, or are unsupported by, and situated circumferentially nearer to or farther from, the said frame. Thus, it will be seen that by adjusting the shell angularly upon the shaft 13, parts of that shell adjacent to or supported directly by, the frame 11, can be brought to bear upon the printing surface 2, to exert the maximum pressure on that surface, or alternatively parts of the said shell unsupported by the frame 11 and nearer and nearer approaching the gap 19 can be thus brought to bear, to exert gradually reducing pressures. As will be obvious, the shell 18 need extend around the frame 11, no farther than is necessary to afford an adequate support and attachment. The wiper 10 may, by any of the well-known means, be axially reciprocated while in contact with the rotating plate cylinder 1, but this feature constitutes no part of the present invention.

In the arrangement shown in Fig. 3, the wiper 10 is in the form of a complete cylinder that is to say, unlike that previously described, it has no gap in its cylindrical wall, and its resilience or flexibility is obtained by reducing the thickness of this wall as at the part 20; the pressure this wiper is caused to exert upon the plate cylinder 1, can be varied by moving the said wiper, together with its shaft 13, bodily nearer to or farther from the axis of the plate cylinder.

In the construction of wiper shown in Fig. 4, the security against rotation is obtained by an arm 21 fast to the frame 11, engaging with a stationary stop 22. In the arrangement as here illustrated, no provision is made for angularly adjusting the wiping shell 18, but it will be readily seen that va-

rious means may be provided for the purpose, for example, the arm 21 may be angularly adjustable on the shaft 13 relatively to the shell 18, or the arm 21 or stop 22 may be provided with an adjustable set screw.

In the arrangement shown in Fig. 5, the wiper is, or may be, of substantially the same construction as that shown in Figs. 1 and 2, the principal feature of difference residing in the fact that, in the example now under review, the shell 18 is thicker than is the shell of the earlier example, and that the desired degree of flexibility is obtained by means of a groove 23 which extends 15 throughout the length of the shell. The degree of pressure which this last described wiper is caused to exert on the printing surface 2, can be varied by adjusting the shell 18 angularly about the axis of the shaft 13 either in the manner before described with 20 reference to Figs. 1 and 2, or otherwise, the pressure decreasing, the nearer the line of contact between the wiper 10 and surface 2 approaches the gap 19.

25 In the arrangement illustrated in Fig. 6, there are provided two closely-concentric shells 18 and 18^a, each substantially like the shell 18 in Fig. 1, and of which the inner one (18^a) serves to reinforce the outer one 30 and has a gap of greater width than has such outer one; if desired, there may be three or more such shells, instead of the two represented. The adjustment for varying the effective pressure exerted by the wiper, 35 may be effected by the means herein described with reference to Fig. 1, or in any other convenient manner.

In the arrangement illustrated in Fig. 7, 40 the shell 18 is of substantially the construction shown in Fig. 1, but, as distinguished from the arrangement shown in that figure, the pressure exerted by the shell is varied by longitudinally adjusting a wedge 24 in a direction parallel with the axis of the 45 shaft 13, the said wedge being guided in, and at one edge bearing against, a block or bar 25 fast to the shaft 13, and at the other

edge bearing against a bar 26 fast to the inner side of the shell 18. The adjustment of the wedge 24 may be effected by a screw or 50 any other convenient means.

Having thus described my invention what I claim and desire to secure by Letters Patent of the United States is as follows:—

1. In a device for wiping an intaglio printing surface, the combination with a shell in the form of part of a cylinder, of a rigid frame to which the shell is attached at one of its longitudinal edges, and a shaft concentric with the shell and to which the frame is attached.

2. In a device for wiping an intaglio printing surface, the combination with a shell in the form of part of a cylinder, of a rigid frame to which the shell is attached at 65 one of its longitudinal edges, a shaft concentric with the shell and to which the frame is attached, and means adapted to vary the resistance opposed to the movement of the shell toward the shaft.

3. In a device for wiping an intaglio printing surface, the combination with a shell in the form of part of a cylinder, of a rigid frame to which the shell is attached at 70 one of its longitudinal edges, a shaft concentric with the shell, and on which the frame is angularly adjustable, and means for effecting such adjustment.

4. In a device for wiping an intaglio printing surface, the combination with a 80 shell in the form of part of a cylinder, of a rigid frame to which the shell is attached at one of its longitudinal edges, a shaft concentric with the shell, and on which the frame is angularly adjustable, means for effecting such adjustment, and locking means 85 for securing the frame and shell in adjusted position.

In witness whereof I have hereunto set my hand in the presence of two witnesses. 90

KARL RÖGER.
